METHOD OF MAKING CONCRETE CONDUITS

Henry E. Lindas, Wichita, Kans.

Application April 4, 1932, Serial No. 603,138

3 Claims. (Cl. 25—155)

The present invention relates to a conduit core, and method for casting concrete conduit.

Various types of inflatable cores have been devised for the casting of concrete conduit and one of the principal difficulties in using a core of this type lies in the fact that the core has a tendency to adhere to the molded conduit when completed, and thus renders difficult and sometimes impossible the withdrawal of the core.

10 An object of the present invention is to make an improved and simplified core for the casting of a conduit.

Another object is to improve the method of casting cementitious conduit.

15 In order to attain these objects, there is provided, in accordance with one feature of the invention, an inflatable core constructed of rubber impregnated fabric or cords with the threads of the fabric or the cords normally disposed at an angle of less than forty-five degrees to a longitudinal plane bisecting the core.

This and other features of the invention, will be more fully brought out in the following description and the accompanying drawing, where-
25 in:

Figure 1 is a view in side elevation of an end portion of a conduit core embodying the present invention, parts being broken away to show the structure of the device.

30 Figure 2 is a sectional view on the line 2—2 of Figure 1.

Figure 3 is a sectional view of a split retaining collar.

Figure 4 is a view in side elevation of the collar shown in Figure 3.

Figure 5 is a diametric view of a section of the fabric used in constructing the expandable core with the threads of the fabric in normal position.

Figure 6 is a view, similar to Figure 5, with the threads in the position they occupy after expansion of the core.

Figure 7 is a sectional view through a quadruple trench showing therein successive stages in the formation of a conduit in accordance with the present invention.

Figure 8 is a view in side elevation of a deflated core member, the central portion thereof being broken away, the dotted lines indicating the diametric expansion and longitudinal contraction which takes place upon inflation of the core.

50 Figure 9 is a view in side elevation of an expanded core in position in a conduit, the conduit being shown sectionally, the center portion being broken away.

55 Figure 10 is a sectional view of a conduit showing

an expansion joint in section thereon, portions of the expansion joint being broken away; and

Figure 11 is a view in perspective of an end compression and retaining member.

Referring to the drawing in detail, a core member A is constructed of superposed layers 1 and 2 of fabric or cord material having the threads or cords thereof disposed at an angle of approximately thirty degrees, with a plane bisecting the longitudinal axis of the core. Figure 5 shows the cords or threads in their normal position, and Figure 6 shows them in the position they occupy when the core is inflated. These cords or threads are impregnated with and imbedded in rubber 3 in the manner of automobile tire fabric, or cords, and are then heated to vulcanize the rubber into a homogeneous mass with the cords or threads imbedded therein.

The ends of the cores are provided with threaded connections as shown in Figure 1. In order to provide these connections, an exteriorly threaded stem 4, having an integral enlarged head portion 5, is positioned with the head 5 thereof within the end of a core A. A small amount of unvulcanized rubber 6 is then placed over the outer face of the head 5 and the open end of the core A is drawn closely around the threaded stem member 4 by means of a split collar 7 which is drawn into close retaining position with the open end of the core, as by means of screws 8 and 9 to firmly grip the end of the core to compress it tightly against the threaded exterior of the tubular member 4. A mass of unvulcanized rubber 10 is then packed around the core between the inner face of the collar 7, and the end of the core. A second mass 11, of unvulcanized rubber, is then placed on the outer face of the collar 7, the word "outer" being used to refer to the direction toward the open end of the core, and the word "inner" to the direction toward the body of the core. A skirt member 12, having a tapered inner surface adapted to coincide with the tapered outer surface of the collar 7, is provided with a central opening 13, of a size to have a free slide fit over the threaded stem portion 4. A nut 14 is then threadedly mounted on the stem 4 and is drawn down to force the skirt member 12 inwardly to exert a cam-like compressing action on the collar 7.

When thus provided with threaded end members, successive lengths of core may be connected together by means of ordinary pipe unions 15.

It is imperative, of course, that the cementitious material, such as concrete, of which a conduit is formed around the present type of core, be not

allowed to surround the end portion of the cores and the unions connecting successive lengths of conduit. In order to prevent these connections from becoming imbedded in the cementitious conduit material, sleeves 16 which may be of metal tubing, having an internal diameter equal to that of the core when expanded, are slipped over each of the connections of successive lengths of core when completed. These joint enclosure members 10 are of a length to overlap the core on each side of the connection, as indicated at 17, so that the expanded core fills and seals these tubular connections against the entrance of conduit material therein.

15 It is necessary and desirable to provide for expansion in the conduit and this may be accomplished by means of ordinary steam-line expansion joints B, such as shown in Figure 10. These expansion joints may be inserted at distances determined by the engineer in charge of installation and will depend, of course, on the nature of the soil in which the conduit is buried and the probable temperature differences which will be encountered. The well known type of joint illustrated comprises a sleeve 18, which is slidably mounted in a casing 19 in which a packing ring, not shown, is held in close contact with the sleeve 18 by means of a collar 20, held in position by means of bolts 21 and nuts 22.

30 The expansion joint used should be for the same pipe size as the diameter of the core when inflated, and, if desired, short lengths of pipe 23 and 24 may be threadedly inserted, one in each end of the expansion joint, to more firmly bind the expansion joint to the sections of concrete conduit which it connects. These expansion joints may be slipped on over the core while the core is deflated and positioned at desirable intervals. When the core is inflated, it will fill, 35 and thereby seal, the ends of the joints or the pipes 23 and 24 against the admission of the cementitious conduit material.

Operation

45 In forming a conduit in accordance with the present invention, a trench 25 (see Figure 7) is dug and is lined with side boards 26 and 27. The core A is then laid alongside the trench and expansion joints B are slipped onto the core at required points, and sleeves 16 are also mounted over each of the connections 15 between core sections. The core is then pumped full of fluid, which may be either water or air, to the required 50 pressure to expand the core to the dotted line position shown in Figure 8. Conduit material 28, which may be concrete, is then poured into the trench 25 and the core A is partially embedded in the concrete while soft, as indicated in the second trench from the left in Figure 1. The core is 55 thereafter covered with a layer of concrete 29 and corner forming beads 30 and 31 are pressed into the sides of the concrete to round out the upper side thereof. The concrete is permitted to harden, whereupon the fluid filling the core A is pumped out. This permits the core to contract to 60 its original diameter and to elongate, as shown in solid lines in Figure 8. This contraction and elongation, due to the inherent elasticity of the

core, pulls it free of the side walls and facilitates its withdrawal from the completed conduit.

The side boards 26 and 27, and the corner beads 30 and 31, may then be removed, and the trench 25 filled with dirt, leaving the completed conduit 80 buried in the earth.

In pouring the concrete for the conduit, the expansion joints B are left uncovered or imbedded in asphalt or tar, as indicated in Figure 10, while the sleeves 16 and 17, illustrated in Figure 9, are covered with concrete and remain imbedded therein after withdrawal of the core.

The core is simple and relatively inexpensive to manufacture, has a uniform rate of expansion up to a point where the cords or threads of which it is fabricated reach an angle of approximately fifty-two degrees to a plane passing through the longitudinal axis of the core, and thereafter resists further expansion. The lateral contraction of the core, upon deflation, combined with the elongation thereof, frees the core from the conduit walls and permits its easy withdrawal, thereby overcoming what has heretofore been one of the principal difficulties attendant upon the use of inflatable cores in the making of concrete conduit.

I claim:

1. The method of making concrete conduit, which comprises molding plastic cementitious material around a tubular conduit core having the walls thereof of rubber with reinforcing fabric embedded therein, a warp and weft of said fabric crossing each other at an acute angle and the warp and weft being each normally disposed at an angle to a longitudinal plane bisecting said core, of less than an angle of maximum resistance to lateral expansion of said core while, said core is inflated to a pressure which will vary the angle of said warp and weft with respect to said longitudinal bisecting plane to an angle approaching 110 said angle of maximum resistance, and of deflating said core and withdrawing it from said cementitious material after said cementitious material has hardened.

2. The method of building a concrete conduit 120 comprising inserting an elongated fluid tight elastic core having restricted ends into oppositely disposed ends of thin stiff tubes and locating the same so that only the opposed ends of the tubes and ends of the core overlap, encasing both said tubes and inflated core in wet concrete, drying the concrete and deflating and removing the core through one of said tubes.

3. The method of making concrete conduit, which comprises covering a tubular core member, materially expansible diametrically and contractible longitudinally on expansion, with wet cementitious material while said tube is in an inflated condition, allowing said material to harden around the core while the core is expanded, then deflating the core causing the core to contract diametrically and expand longitudinally sufficient to separate the core from the interior of the hardened cementitious material and afterwards withdrawing said core from said hardened cementitious material.

HENRY E. LINDAS.
